RING MOLD

Adrien L. Langel, Chicago, Ill., assignor to Chicago Metallic Manufacturing Company, Chicago, Ill., a corporation of Illinois

Application December 2, 1940, Serial No. 368,164

15 Claims.

(Cl. 53—6)

My present invention, which relates to a three-part ring mold, is concerned particularly with a means for preventing leakage at the joints thereof. Ring molds of the type commonly used for baking have in the past been subject to leakage at the points of connection between the ends of the ring, and around the edges of the bottom which is fitted into the ring. It is the primary object of my invention to provide a convenient and inexpensive means for preventing any such leakage. The parts which enter into the construction by which these objectives are gained, are simple, inexpensive and easily assembled. A suggestive embodiment of my invention is set forth in the accompanying drawings, wherein—

Figure 1 is a perspective view of the ring mold in its entirety;

Fig. 2 is an enlarged detail in cross-section, taken on line 2—2 of Fig. 1;

Fig. 3 is a perspective view in detail of the clip applied to the ring mold to lock its ends together;

Fig. 4 is a perspective view in detail showing the ends of the ring mold separated;

Fig. 5 is a view in perspective of the clip locking toward its inner side;

Figs. 6 and 7 are enlarged details in section taken, respectively, on lines 6—6 and 7—7 of Fig. 1;

Fig. 8 is a detail in elevation of the ring mold joint, adjacent the lower end, showing a modified construction;

Fig. 9 is a view in perspective showing a locking clip applied to a joint of still different construction;

Fig. 10 is a perspective view of the clip perse which is shown in connection with Fig. 9;

Fig. 11 is an enlarged detail in section, taken on line 11—11 of Fig. 9; and

Fig. 12 is a fragmentary view in elevation showing the joint as used with the constructions of Figs. 9—11.

The ring mold of my invention is shown best in Figure 1. My ring mold consists principally of an elongated strip 15, as of sheet metal, curved or bent through 360° so as to present its opposite ends, 16 and 17, in meeting relation. The upper edge of the strip 15 is outwardly curled, and disposed therein and secured thereunder is a wire reinforcement 19, coextensive in length with the strip 15. One end 20 of the wire reinforcement 19 protrudes beyond the strip end, and the other end terminates a corresponding distance short of the other strip end (see Fig. 4), thus

providing a recess to accommodate the protruding wire end 20 when the ends 16 and 17 of the strip 15 are in butt relation.

As here shown, the lower edge 23 of the strip 15 is curled inwardly slightly more than 90°. A bottom plate 24 having depending rolled edges 25 is adapted, when placed within the ring, to interfit its rolled edges 25 with the inwardly curled lower edge 23 of the strip, thereby providing an easily removable, leak-proof bottom for the ring mold.

The ends 16 and 17 of the strip 15 are provided with flanges 26 and 27, respectively, outwardly and reversely bent and extending from a point near the upper edge 18 of the strip toward the lower edge 23, but terminating short of the latter. The lower ends of each flange slant outwardly as at 28 so as to aid in guiding the clip, presently to be described, over the flanges.

A tongue 29 extends laterally from one end, here indicated as the end 17, of the strip in the region adjacent its lower edge 23, and below the flange 27. This tongue is adapted for overlap with the opposite strip end 16, when the two strip ends are otherwise in butt relation. By means of this overlapping connection between the two ends I prevent the leakage which might otherwise occur at the joining ends of the strip.

A hollow spring clip C is adapted to form a releasable interlock between the two strip ends 16 and 17. This clip as shown in Figs. 3 and 5 comprises an elongated strap 31 of sheet metal formed with sides 32, and over the greater part of its length with inner walls 36 and 37 separated from each other and from the strap 31 so as to provide a channel wherein the oppositely extended flanges 26 and 27 are adapted to be slidably received. The inner walls 36 and 37 are approximately coextensive in length with the flanges 26 and 27. The portion of the clip which lies below the flanges is formed to provide a hollow pocket defined by the sides 32 and the strap which is inwardly curved at its lower end. This pocket is adapted to catch any dough or like material, which may pass through the joint, thereby preventing any spilling or leaking. The clip near its upper end is provided with a transverse outset channel 38 wherein the reinforced upper edge 18 of the strip is adapted to be received. I thereby form a spring lock which, being resilient enough to yield and permit movement of the reinforced upper edge 18 into or out of the channel, yet tending when so positioned to maintain itself fixedly in place, snaps tightly

over the upper edge of the strip when the clip is applied to the ring mold.

The upper end of the clip may terminate in an outwardly extending tab 39 convenient for manipulation. As here shown, the clip is formed in its upper region with an outwardly projecting rib 40 extending lengthwise of the clip to provide a reinforcement for the spring lock. The lower end 41 of the clip is curled inwardly and then upwardly, and is adapted to fit snugly 10 against the joint between the strip ends and to extend lengthwise along the inward curl of the lower edge 23 of the strip 15. This curve may be likewise reinforced as by a longitudinally extending rib 42 disposed in the lower region of 15 the clip.

The clip is properly positioned by sliding it upwardly over the flanges 26 and 27 until the curl 41 at the lower end of the clip is tight against the lower edge of the strip 15, and the spring lock of the clip is snapped over the upper edge 18 of the strip. When the clip is in place my ring mold is complete, and there is no possibility of leakage through any of the joints.

In Fig. 8 I show a slightly modified construction. The strip ends are here formed with tongues 29 (in dotted lines) and 30, adapted to interfit when the ring ends are otherwise in butt relation. As here shown the tongue 29 is fitted within the tongue 30.

A modified form of my invention is shown in Figs. 9-12. The lower end 43 of the clip strap 31 is inset and adapted when the clip is in place to directly engage the exterior surface of the mold. A longitudinal, inwardly projecting rib 44 is formed centrally of the clip lower end which is desirably inwardly curled at 45 through 90° or more. This rib serves the dual purpose of reinforcing the clip, and of fitting into a slot 46 which may intervene between the strip ends in 40 the lower region of the mold, the rib then acting as a closure therefor to prevent leakage therethrough.

The present ring mold has advantages from several standpoints. The clip which provides the 45 releasable interlock for the two ends of the mold is held in place by its own spring action, and consequently requires no aid from any tool when it is applied or removed. It may be made of lightweight sheet metal, and still be amply strong to fulfill the requirements for which it is designed due, in part, to the provision of the embossed reinforcements which extend longitudinally thereof in each end region to provide the needed strength. This clip, while serving conveniently as a releasable lock for the mold ends, also acts to prevent the leakage of dough or other contents which may be expressed from the mold during the process of baking. This is an important consideration because it confines the dough to the interior of the mold, thus obviating an unsanitary, unclean, and generally unsatisfactory condition within the oven where baking takes place. The joint between the mold ends is also considerably improved by the overlapping tongue or tongues at the point where the leakage problem is usually most serious. The locking clip serves to maintain the meeting ends of the mold in their closed relation, and in addition offers an exterior closed chamber, in its lower end, into which spilled dough may possibly escape, in case of leakage. If it be preferred not to employ one or more laterally extending tongues which overlap, then the provision of an open joint which is adapted to be closed by the 70

reinforced rib at the lower end of the clip will serve effectively as a closure to prevent the escape of the contents from the mold.

In use, the mold may be readily disassembled 5 by first removing the clip which frees the mold ends for separation, the bottom then disengaging of its own accord. Each of these parts is then free for individual handling and cleaning, and no difficulty will be encountered in removing any spilled dough which may possibly have collected on the inside of the clip or in the joint between the two ends of the mold. Accordingly, by the improved features of this construction, the mold may be maintained in a perfectly sanitary condition, and in case of damage to any of its parts the substitution of a new, fresh part will involve no difficulty whatsoever.

I claim:

1. A ring mold having separable meeting ends, 20 a clip separable from the mold formed to extend over the joint between the meeting ends thereof, interengaging means on the clip and mold ends providing a slideable interlock therebetween, and interengaging means one of which is yieldable provided on the clip and mold cooperating to 25 form a releasable lock therebetween whereby to permit or prevent sliding movement of the clip toward and from operative locking position relative to the mold.

30 2. A ring mold having separable meeting ends one of which is formed with a tongue extending laterally to lap past the other at a point adjacent the mold lower edge, and a clip independent of the mold adapted for interlock with the meeting ends of the mold and provided with an inwardly curved lower end adapted to underlie the joint produced by the overlapping tongue, the walls of the clip above its curled lower end being fashioned to closely fit against the outer surface of the mold on opposite sides of the joint, and resilient means for securing the clip in its operative locking position.

3. A ring mold having meeting ends providing a joint therebetween, a clip extensible along the joint and engageable with the ends of the mold to 45 provide a releasable interlock therefor, the clip being formed to present spaced walls in engagement with the mold exterior on opposite sides of the joint between the mold ends, and resilient means for securing the clip in operative locking position upon the mold.

4. A ring mold having meeting ends providing therebetween a joint, a clip separable from the mold and applicable to the meeting ends of the 55 mold to provide an interlock therebetween, the clip being formed of sheet metal with its lower end curved to underlie the bottom edge of the mold and with means extended transversely of its upper end for releasable engagement with the corresponding edge of the mold, and reinforcing means extending longitudinally of the clip in the regions of its two ends engaging with portions of the mold adjacent its opposite edges adapted to sustain the clip ends in firm engagement with opposite edges of the mold.

5. A ring mold having meeting end providing a joint therebetween, a clip separable from the mold releasably applicable to the meeting ends of the mold to provide an interlock therebetween, the clip being formed with spaced walls engageable with the mold at point on opposite sides of the joint, and means for releasably holding the clip against displacement from its operative locking position upon the mold.

6. A ring mold having meeting ends providing

therebetween a joint with an intervening space defining a slot in its bottom region, a clip separable from the mold and releasably applicable to the ends thereof for providing an interlock therebetween, the clip being formed with walls adapted to engage the mold exterior at points along opposite sides of the joint and with an inwardly protruding rib extending lengthwise thereof adapted to enter the slot between the meeting ends of the mold to provide a closure therefor.

7. A ring mold having meeting ends providing therebetween a joint with an intervening space defining a slot in its bottom region, a clip separable from the mold and releasably applicable to the ends thereof for providing an interlock therebetween, the clip being formed with an inwardly protruding rib extending lengthwise thereof adapted to enter the slot between the meeting ends of the mold to provide a closure therefor.

8. A ring mold having meeting ends providing therebetween a joint with an intervening space defining a slot in its bottom region, a clip separable from the mold and releasably applicable to the ends thereof for providing an interlock therebetween, the clip being formed at its lower end with an inward curl adapted to underlie and closely engage the mold bottom edge and with an inwardly protruding rib extending lengthwise thereof in its lower region and into the curled end thereof adapted to enter the slot between the meeting ends of the mold to provide a closure therefor.

9. A ring mold in the form of an elongated strip which is bent through 360° to present its opposite ends in meeting relation, a bottom plate adapted to fit removably within the ring, a spring clip forming a releasable interlock between the two ring ends, the clip at its upper end having means adapted to engage the upper ring edge and at its lower end having means adapted to engage the lower ring edge, the clip being sufficiently resilient to tend to maintain itself fixedly in place, when disposed in its normal interlocking position, and to yield as required for movement to or from that position.

10. A ring mold of sheet metal with opposite ends disposed in meeting relation, means exteriorly of the mold engageable with the ends thereof to provide an interlock therefor, one of the engaged parts being yieldable with respect to the other whereby to releasably support the interlocking means in operative position, one of the mold ends adjacent its bottom being extended laterally past the other inlapping relation thereto, and the interlocking means being formed to extend over and around the lapping joint thus produced between the two mold ends to provide an outer closure therefor.

11. A ring mold in the form of an elongated sheet metal strip which is bent through 360° to present its opposite ends in meeting relation, the upper edge of the ring being outwardly curled, a wire reinforcement coextensive in length with the strip disposed within and secured by the curled ring edge with one end of the wire protruding beyond the supporting ring end and the other wire end terminating a substantially corresponding distance short of its supporting ring end whereby to provide a recess for accommodating the protruding wire end when the two ends of the ring are in meeting relation, a flange at each ring end outwardly and reversely bent and extending for a substantial distance across the ring between its upper and lower edges but terminating short of

the latter, an inward curl of more than 90° extending along the lower ring edge, a bottom plate having depending rolled edges extending into a lower plane adapted, when placed within the ring, to interfit its rolled edges with the inwardly curled lower edge of the ring, one end of the ring in the region adjacent its lower edge being provided with a tongue extended laterally below the proximate flange adapted for overlap with the opposite ring end when the two ring ends are in meeting relation, and a hollow spring clip forming a releasable interlock between the two ring ends, the clip being split to provide spaced walls affording a channel wherein the oppositely extended flanges are adapted to be slidably received, and near its upper end being formed with an outset transverse channel wherein the outward protruding reinforcement at the upper ring edge is adapted to be received and at its lower end with a curl extending inwardly and then upwardly adapted to underlie the joint between the ring ends and extend lengthwise along the ring oppositely therefrom, the clip upper end being sufficiently resilient to yield as required for movement of the reinforced upper ring edge into or out of the channel extending transversely of the clip whenever the clip is applied to or removed from the ring end, and, when disposed in its normal interlocking relation with the ring flanges, tending to maintain itself fixedly in place.

12. A ring mold in the form of an elongated sheet metal strip which is bent through 360° to present its opposite ends in meeting relation, the upper edge of the ring being outwardly curled, a flange at each ring end outwardly and reversely bent and extending for a substantial distance across the ring between its upper and lower edges, an inward curl extending along the lower ring edge, a bottom plate having depending curled edges adapted, when placed within the ring, to interfit its edges with the inwardly curled edge of the ring, the ends of the ring in the region adjacent its lower edge being provided with tongues extended laterally below the proximate flanges each adapted for interfitting with the tongue of the opposite ring end when the two ring ends are in meeting relation, and a hollow spring clip forming a releasable interlock between the two ring ends, the clip being formed with spaced walls affording a channel wherein the oppositely extended flanges are adapted to be slidably received, with an outset channel at its upper end wherein the curled upper ring edge is adapted to be received, and with means at its lower end defining a hollow pocket adapted to overlie the joint between the ring ends, the clip at its lower extremity being curled inwardly and then upwardly adapted to underlie the joint between the ring ends and extend lengthwise along the ring oppositely therefrom, the clip upper end being sufficiently resilient to yield as required for movement of the upper ring edge into or out of the channel extending transversely of the clip whenever the clip is applied to or removed from the ring ends, and, when disposed in its normal interlocking relation with the ring flanges, tending to maintain itself fixedly in place.

13. A ring mold in the form of an elongated sheet metal strip which is bent through 360° to present its opposite ends in meeting relation with an intervening slot in the lower region thereof, the upper edge of the ring being outwardly curled, a flange at each ring end outwardly and reversely bent and extending for a substantial distance across the ring between its upper and lower edges but terminating short of

lower edges but terminating short of the latter, an inward curl extending along the lower ring edge, a bottom plate having depending curled edges adapted, when placed within the ring, to interfit its curled edges with the inwardly curled lower edge of the ring, and a spring clip forming a releasable interlock between the two ring ends, the clip being formed with spaced walls affording a channel wherein the oppositely extended flanges are adapted to be slidingly received, and at its upper end being formed with an outset channel wherein the curled upper ring edge is adapted to be received, and at its lower end being inset to engage the joint between the ring ends, a central longitudinal rib reinforcing the outset channel, a central inset rib adapted to fit within the slot between the ring ends, a curl extending inwardly and then upwardly from the extreme lower end of the clip adapted to underlie the joint between the ring ends and extend lengthwise along the ring oppositely therefrom, the clip upper end being sufficiently resilient to yield as required for movement of the upper ring edge into or out of the channel extending transversely of the clip whenever the clip is applied to or removed from the ring end, and, when disposed in its normal interlocking relation with the ring flanges, tending to maintain itself fixedly in place.

14. A ring mold in the form of an elongated sheet metal strip which is bent through 360° to present its opposite ends in meeting relation, the upper edge of the ring being outwardly curled, a flange at each ring end outwardly and reversely bent and extending for a substantial distance across the ring between its upper and lower edges, an inward curl extending along the lower ring edge, a bottom plate having depending curled edges adapted, when placed within the ring, to interfit its curled edges with the inwardly curled lower edge of the ring, one end of the ring adjacent its lower edge being provided with a tongue extended laterally below the proximate flange adapted to overlap the opposite ring end when the two ring ends are in meeting relation, and a hollow spring clip forming a releasable interlock between the two ring ends, the clip being formed with spaced walls affording a channel wherein the oppositely extended flanges are adapted to be slidingly received, and at its upper

end being formed with an outset channel wherein the curled upper ring edge is adapted to be received, and with means at its lower end defining a hollow pocket adapted to overlie the joint between the ring ends, the clip at its lower extremity being curled inwardly and then upwardly adapted to underlie the joint between the ring ends and extend lengthwise along the ring oppositely therefrom, the clip upper end being sufficiently resilient to yield as required for movement of the upper ring edge into or out of the channel extending transversely of the clip whenever the clip is applied to or removed from the ring end, and, when disposed in its normal interlocking relation with the ring flanges, tending to maintain itself fixedly in place.

15. A ring mold in the form of an elongated sheet metal strip which is bent through 360° to present its opposite ends in meeting relation, the upper edge of the ring being outwardly curled, a flange at each ring end outwardly and reversely bent and extending for a substantial distance across the ring between its upper and lower edges but terminating short of the latter, an inward curl extending along the lower ring edge, a bottom plate having depending rolled edges extending into a lower plane adapted, when placed within the ring, to interfit its rolled edges with the inwardly curled lower edge of the ring, and a hollow spring clip forming a releasable interlock between the two ring ends, the clip being formed with spaced walls affording a channel wherein the oppositely extended flanges are adapted to be slidingly received, and at its upper end being formed with an outset transverse channel wherein the outwardly protruding upper ring edge is adapted to be received and at its lower end with a curl extending inwardly and then upwardly adapted to underlie the joint between the ring ends and extend lengthwise along the ring oppositely therefrom, the clip upper end being sufficiently resilient to yield as required for movement of the reinforced upper ring edge into or out of the channel extending transversely of the clip whenever the clip is applied to or removed from the ring end, and, when disposed in its normal interlocking relation with the ring flanges, tending to maintain itself fixedly in place.

ADRIEN L. LANGEL.
